UNITED STATES PATENT OFFICE.

JAMES G. WILSON, OF NEW YORK, N. Y.

COMBINED ROLLING AND FOLDING SHUTTER.

SPECIFICATION forming part of Letters Patent No. 663,554, dated December 11, 1900.

Application filed June 13, 1900. Serial No. 20,174. (No model.)

To all whom it may concern:

Be it known that I, JAMES GODFREY WILSON, a subject of Victoria, Queen of Great Britain, residing at New York, in the county 5 of New York and State of New York, have invented certain new and useful Improvements in a Combined Rolling and Folding Shutter; and I do hereby declare the following to be a full, clear, and exact description of the 10 invention, such as will enable others skilled in the art to which it appertains to make and use the same.

My invention relates to certain new and useful improvements in combined rolling and 15 folding shutters such as are to be used in connection with large windows and doors, and has for its object to improve the appearance of the shutter and to make it stronger, more durable, and quicker in operation and more 20 economical in cost.

With these ends in view my invention consists in the details of construction and combination of parts, such as will hereinafter be 25 fully set forth and then specifically designated by the claims.

In the accompanying drawings, which form a part of this application, Figure 1 is a front elevation showing my improved shutter in closed condition. Figs. 2 and 3 are sectional 30 elevations at the line $\alpha\alpha$ of Fig. 1 and showing, respectively, the position of the parts of my improvement when the shutter is lowered and raised; Fig. 4, a detailed broken elevation, on an enlarged scale, showing the two upper leaves in folded condition and the manner 35 of attaching the upper short leaf to the angle-iron which is secured to the lower edge of the rolling shutter, and also showing, in side elevation, the trunnion on the lower leaf; and 40 Fig. 5 is a detail broken sectional elevation showing the construction of the shutter and trunnion guides, with the end of one of the shutters in position therein.

Similar numbers of reference denote like 45 parts in the several figures of the drawings.

Prior to my invention the ordinary corrugated iron rolling shutter has been commonly used, and I therefore do not wish to be understood as laying any claim to such construction.

1 is the usual corrugated iron shutter, capa-

ble of being rolled over the drum 2, secured in position at the top of the door, the ends of said shutter being guided within ways 3 and 9 at the sides of the doorway.

55

4 is an angle-iron which is secured to the lower edge of the rolling shutter. 5 is a plain leaf-shutter one of whose edges is hinged at 6 to this angle-iron, 7 is also a plain leaf-shutter which is hinged at one of its edges 60 to the free edge of the leaf 5, and 8 is also a plain leaf-shutter one of whose edges is hinged to the free edge of the leaf 7, these points of hinging referred to being so arranged that the leaves will fold in reverse directions, 65 as will be presently explained.

The ways 9 at the sides of the doorway extend upward only a distance substantially equal to the combined widths of the leaves 5, 7, and 8. 10 11 are trunnions which extend 70 axially from the ends of the leaves 7 8 and are preferably provided with friction-rolls 12 13, and 14 15 are cords or cables secured to these trunnions at each side of the leaves and passed upwardly over the grooves of double 75 pulleys 16 17, that are suitably journaled above the doorway and at each side thereof, and to these cords are attached weights 18 19.

The ways 3 and 9 are in vertical alinement and are practically a continuation one of the 80 other; but the ways 9 are a trifle wider and extend inwardly, so as to inclose the ends of the leaves when the latter are in closed position. The trunnions 10 11 are always within the ways 3, so that it will be readily understood that the shutters will always be guided in a true vertical plane by reason of the fact 85 that they are properly centered by these trunnions. The cords 14 are secured to the trunnions 10 and are passed up through the ways 90 over one set of grooves in the pulleys 16 17, and from the free ends of these cords the weights 18 depend. The cords 15 are attached to the trunnions 11 and are passed up through the ways over the other set of grooves 95 in the pulleys 16 17, and from the free ends of these cords depend weights 19.

20 is an eye which is secured to the lower leaf 8 for convenience in operating the shutter, both in elevating the same and in pulling 100 it down by any suitable means.

The construction, arrangement, and opera-

tion of the corrugated iron element of the shutter are usual and ordinary and require no description or detailed illustration herein.

Presupposing the shutter to be in closed condition, as shown at Fig. 1, if the same is now raised the leaves will maintain their relation in the same vertical plane until the lowest leaf has been raised clear of the guideways 9, and then the action of the weights 10 upon the leaves 7 8 will cause the same to rapidly fold up into the position shown at Fig. 3, the trunnions meanwhile preserving their position within the guideways 3. The ways 9 overlapping, as they do, the shutters 15 at their ends will prevent any folding of the latter on their hinges until the leaves have entirely cleared the ways 9. When it is desired to lower the shutter, any proper hook device is simply engaged with the eye 20, and 20 the leaves are then pulled down in a vertical position and are readily lowered into the position shown at Fig. 1.

Having thus described my invention, what I claim as new, and desire to secure by Letters Patent, is—

1. The herein-described shutter comprising the reversely-hinged leaves suspended from an element capable of being raised and lowered said leaves being provided with trunnions suitably guided within ways, the guideways which inclose the side edges of said leaves, and the cords secured to said trunnions and passed over pulleys and having their free ends connected with weights, substantially as set forth.

2. In a shutter, the combination of the reversely-hinged leaves guided and maintained in a vertical plane throughout a predetermined distance, means for elevating and lowering said leaves in a vertical plane, and

weights connected by cords to the ends of said leaves whereby the latter are caused to fold against each other, substantially as set forth.

3. The combination of the corrugated iron shutter capable of being elevated and lowered and having the angle-iron secured at its lower edge, the narrow leaf having one of its edges hinged to said angle-iron, the upper and lower wide leaves hinged together while the free edge of the upper leaf is hinged to the narrow leaf, the guideway extending at the sides of the doorway throughout its height, the trunnions extending from the wide leaves into said guideway, the guideway at the sides of the doorway and extending throughout a portion of the height of the latter and inclosing the ends of said leaves, the pulleys suitably supported at the top of the doorway at each side thereof, and the weighted cords passed over said pulleys and having their free ends connected to said trunnions, substantially as set forth.

4. In a shutter, the combination of a series of leaves hinged to each other so as to fold in horizontal disposition alternately in opposite directions, means for elevating and lowering said leaves while in extended condition, means for axially guiding said leaves, a guideway for holding said leaves as against folding on their hinges throughout a predetermined extent of their elevation while in extended condition, and means for effecting the folding operation of said leaves after they have cleared said guideway, substantially as set forth.

In testimony whereof I affix my signature in presence of two witnesses.

JAS. G. WILSON.
